UNITED STATES PATENT OFFICE.

CLAIR DENNISON LAKE, OF BINGHAMTON, NEW YORK, ASSIGNOR TO THE TABULATING MACHINE COMPANY, A CORPORATION OF NEW JERSEY.

PRINTER-RIBBON-CONTROL MECHANISM.

Application filed August 30, 1921. Serial No. 496,876.

To all whom it may concern:

Be it known that I, CLAIR D. LAKE, a citizen of the United States of America, residing at Binghamton, in the county of Broome and State of New York, have invented certain new and useful Improvements in Printer-Ribbon-Control Mechanism, of which the following is a full, clear, and exact description.

10 In prior applications for Letters Patent filed by me, notably Serial No. 348,069, filed December 29, 1919, and Serial No. 465,868, filed April 30, 1921, I have shown and described tabulating machines of the Hollerith type having in-addition to the regular tabulating mechanism a printing attachment for listing the figures brought by the operation of the machine, to the display window, and for printing totals and sub-totals of any 20 or all of such figures as may be desired.

15 In the use of such machines, it is desirable that the figures corresponding to the punchings of certain cards be printed in ink of a distinctive color, but heretofore no provision for doing this has been devised or used, and it is the object of the present invention to provide means for use in conjunction with the mechanism of the printing attachment and controlled preferably by punched holes 25 in certain columns to print such figures or the totals in a different color, usually red, while the other figures are printed in black or dark blue.

30 In all machines and devices of this general character an inking ribbon is almost universally employed to print the characters set up by the computing mechanism on a strip or sheet of paper, and my present invention consists in an attachment to such a printing mechanism which comprises a ribbon control 35 which operates to shift a two-colored ribbon when so desired, so as to bring under the type from which an impression is to be taken, that part of such ribbon as prints in a distinctive color.

40 This improvement is illustrated in the accompanying drawings.

45 Fig. 1 is a sectional elevation of the entire listing or printing attachment for a tabulating machine, with my improvement applied thereto.

50 Fig. 2 is a front elevation of the listing attachment showing a portion of the tabulating machine with which it is used.

55 Fig. 3 is a front elevation of the ribbon

holder and its operating electromagnet.

Fig. 4 is a sectional elevation of the parts shown in Fig. 3.

Fig. 5 and 6 are detail views in elevation of the parts which effect the ribbon shift.

Fig. 7 is a front elevation of the parts shown in Fig. 6.

Fig. 8 is a plan view of the parts shown in Fig. 6.

Fig. 9 is a wiring diagram sufficient to 65 illustrate the operation of my improvement.

Fig. 10 is a front elevation of a modification showing a multiple ribbon control.

Fig. 11 is a plan view of a modification showing a multiple ribbon control.

Fig. 12 is a section on line 12-12 of Fig. 11.

The listing and total printing attachment is not directly involved in the present improvement, and is a piece of mechanism 75 which is now well known in this art. In Figs. 1 and 2 it is shown in some detail, but a detailed description of its construction and mode of operation is not necessary. Generally speaking, it comprises a series of vertically movable bars 1, carrying or adapted to raise type bars 2 having laterally moving spring actuated type 3 corresponding to the digits in a column on a tabulator card. 80 There are as many type bars as there are 85 registering wheels in the counters of the tabulator, and by means of controlling magnets 4 the vertical movable bars 1 are locked in a position which will bring to the printing position the type 3 which correspond to the 90 perforations in the tabulator cards which pass under the contact brushes.

The bars 1 are moved vertically by means of which a slide 5 constitutes one of the main parts or elements, that is to say, for 95 example, when a figure is to be printed the slide 5 traveling over guides 6 rises and carries up the bars 1 to the proper height to bring the proper type 3 into printing position, and the paper strip 7, passing over a 100 platen or drum 8, is then printed by hammers 9, worked by the machine.

No further description of the printing attachment is necessary herein, for any form of mechanism which contains the elements 105 above enumerated or their equivalents, and which contains a part corresponding to the slide 5, which is raised a sufficient amount each time that a figure is to be printed, will meet the requirements of this case.

The printing attachment carries two ribbon rolls 10, with the usual appurtenances for changing their direction of rotation. The ribbon 11 is carried by the usual guide rolls 12, between the type 3 and the platen 8, but the rolls 12 which support the ribbon in its path immediately in front of the type are carried by levers 13, pivoted to the stationary frame of the machine at 14. The ribbon 10 is the ordinary two colored ribbon, the black or blue half of which is normally in front of the type, or in the printing position, but the red half of which may be brought into this position if the levers 13 constituting the frame support for the front rolls be raised.

Pivottally connected with each one of the levers 13 is a long bar 15, to which is connected a spiral spring 16 that tends to swing the entire long bar 15 to the left, as shown in Figs. 1 and 4. Normally the lower end of this bar rests in contact with the slides 5 as shown in Figs. 1 and 5, and by said slide the bar is forced to the right to a position in which it is held by a catch 17. By 25 this catch it is always held in this its normal position wherever the slide may be or to whatever position vertically it may be moved.

Mounted in the instrument is an electro-magnet 18 the armature 19 of which is rigidly fixed to the catch 17 and when this magnet is energized the catch 17 is lowered out of engagement with a swinging spring actuated locking lever 20 that holds the bar 15 in its normal position. The said bar is therefore free to move on its pivotal connection with the lever 13, and will do so if the slide 5 be raised above its lower end.

To the bar 15 is fixed an arm 21 carrying an adjustable stop 22. When the bar 15 has been unlatched, and the slide 5 rises, the bar swings to the left sufficiently to bring this stop 22 over the edge of the slide, with the result that the bar 15 is raised and the lever 13 is swung upwardly to bring the lower half of the ribbon opposite the type. In order that the parts shall preserve their proper relative positions, the bar 15 carries a cam plate 23 which contacts with the slide 5, as shown in Fig. 6.

Referring now to Fig. 9, this shows a portion of the conventional diagram of a tabulator, which is more fully described in my application Serial No. 465,868, filed April 30, 1921, with the addition of the circuit 24, containing the magnet 18. When it is desired to print in a distinctive color, this circuit is plugged in, in the usual way, and either by a push button or automatically by a punched hole in a card when a figure is to be printed in red, the circuit is closed and the magnet 18 energized. Plugging in of the magnet is effected from the plug socket 35 to the selected plug socket position on the usual tabulator plugboard.

In this way provision is made for causing red imprints to be made on the record sheet when a perforation exists in a column on a card to which the plug connection is made. Furthermore the plug connection permits any selected column to be used for controlling ribbon shifting. As has been set forth above, the ribbon is shifted only after the energization of this magnet, so that while all ordinary listing is printed in black or blue ink, all credit cards, for example, are printed in red.

Contacts 26 and 27 are closed by means of lever 28 which is rigidly fixed to armature 19, when magnet 18 is energized, and the closing of these contacts prevents sparking at the contact brushes when they are leaving the punched hole in card.

The circuit through magnet 18 is broken by cam 29 (Figure 9) while clamped to the attachment rocker shaft #30 is an adjustable lever #31, which through its connection with lever #28, mechanically releases the armature #19 from magnet #18; and the spring #32, upon which contact #26 is mounted, acts to retain the armature #19 in its normal position.

Usually these printing attachments have groups of type corresponding to the several counters of the tabulator, and in the present illustration the attachment is shown as having five of such groups. One ribbon is used for all of such groups, but, as shown in Fig. 12, the ribbon for each group is carried by a frame 25 which is movable, and in order to print in red any group I employ a magnet 18 for each frame 25 and by energizing these magnets the ribbon for that group may be shifted without moving the ribbon in front of any other group. This is manifestly a mere amplification of the principle involved in the structure described by reference to Figs. 1, 5 and 6.

This apparatus affords a very simple and effective solution of the problem of printing certain figures such as credits in distinctive colors in listing attachments for tabulating machines, and adds but very few and easily constructed parts to those necessary for the operation of the main device.

What I claim is:

1. The combination in a listing or printing device of the kind described, with a part or element thereof which moves a given distance during or in connection with each operation of printing, of a shiftable ribbon, a bar adapted by its movement to shift the same, a catch normally holding said bar in an inoperative position, and an electromagnet for releasing said bar and permitting it to come into operative relation with said movable part, whereby it receives therefrom the movement necessary for shifting the ribbon.

2. The combination in a listing or print-

- ing device of the kind described, with a ribbon support normally stationary but adapted to be shifted to present different colored parts of the ribbon to the printing position, 5 of means for shifting the supports for this purpose, an electromagnet, and means controlled thereby for normally holding said shifting means in inoperative position, and means for operating the same to shift the 10 ribbon when said magnet is energized.
3. The combination in a listing or printing device of the kind described, with a ribbon support normally stationary but adapted to be shifted to present different colored 15 parts of the ribbon to the printing position, of a bar pivoted to said supports, a slide constituting an element of the printing device which moves a given distance whenever a figure is to be printed, means for 20 holding said bar in an inoperative position, and an electromagnet which releases said bar and permits it to come into operative relation to said slide and to be raised thereby to an extent sufficient to shift the ribbon.
- 25 4. The combination in a listing or printing device of the kind described, with a ribbon support normally stationary but adapted to be shifted to present different colored parts of the ribbon to the printing position, a spring actuated bar pivotally suspended from said support, a catch normally holding said bar in inoperative position, a slide constituting an element of the printing device which moves a given distance when-
- ever a figure is to be printed, and an electro- 35 magnet for releasing said catch and permitting an adjustable stop carried by said bar to come into the path of the moving slide and thereby to shift the ribbon support.
5. In a tabulating machine or the like, 40 which is adapted to print items derived from perforated records upon a record sheet, means for listing certain items in a different color upon the record sheet, and means for controlling the color of printing the 45 listed records by the perforations in the record cards, said means being adapted to be selectively controlled by any desired record card column.
6. The invention set forth in claim 5 in 50 which a plug connection is utilized for coupling the color controlling means to the desired column of a tabulator plugboard.
7. In a tabulating machine having printer devices controlled by perforated record 55 cards, multi-color ink ribbon means associated with said printing devices, and means including a selecting magnet and a circuit therefor selectively controllable by any desired record card column and controlled during 60 the operation of the tabulating machine for controlling said multi-color devices whereby certain records are made in one color and others in another color.

In testimony whereof I hereto affix my 65 signature.

CLAIR DENNISON LAKE.
